DESIGN FOR A COOKING RANGE

Robert B. McCombe and Paul Schweikher, Chicago, Ill., assignors to Kalamazoo Stove & Furnace Company, Kalamazoo, Mich., a corporation of Michigan

Application April 4, 1941, Serial No. 100,131

Term of patent 14 years

To all whom it may concern:

Be it known that we, Robert B. McCombe and Paul Schweikher, citizens of the United States, residing at Chicago, Cook County, Illinois, have invented a new, original, and ornamental Design for a Cooking Range, of which the following is a specification, reference being had to the accompanying drawing, forming part thereof, in which:

Fig. 1 is a front elevational view of a cooking range, showing our new design.

Fig. 2 is a right hand elevational view, the left hand elevation being a duplicate thereof.

Fig. 3 is a top plan view thereof.

We claim:

The ornamental design for a cooking range, as shown and described.

ROBERT B. McCOMBE.
PAUL SCHWEIKHER.
